UNITED STATES PATENT OFFICE.

J. GEORGE BRILL AND EDWARD H. ZITZMAN, OF PHILADELPHIA, PA.

CAR-AXLE BOX.

SPECIFICATION forming part of Letters Patent No. 312,181, dated February 10, 1885.

Application filed July 21, 1884. (No model.)

To all whom it may concern:

Be it known that we, J. GEORGE BRILL and EDWARD H. ZITZMAN, citizens of the United States, residing at Philadelphia, in the county 5 of Philadelphia and State of Pennsylvania, have invented certain new and useful Improvements in Car-Axle Boxes, of which the following is a specification, reference being had therein to the accompanying drawings, where-
10 in—

Figure 1 is a vertical longitudinal section of an axle-box embodying our improvements. Fig. 2 is a cross-section on line 1 1 of Fig. 1. Fig. 3 is an elevation of the followers for the 15 dust-excluder or packing at rear end of the box, showing the spring mechanism for obtaining the automatic movement of the followers for taking up the wear of the wood or packing-plates, the latter not being indicated. Fig. 4 is a broken top view of one of the followers. Fig. 5 is a side or edge elevation of a follower. Fig. 6 is a broken horizontal section through the oil-conduit. Fig. 7 is a trans- 20 verse section of a paddle or oil-forcing wheel having adjustable blades or paddles. Fig. 8 is a rear elevation of axle-box. Fig. 9 is a 25 plan, partly sectional, of same; and Fig. 10 is a broken elevation of one of the wooden or packing plates for the dust-excluder at rear end 30 of box.

Our invention has relation to improvements in axle-boxes, having particular reference to devices for oiling the axle-journal and its bearing, to shields and packing for excluding dust 35 and dirt and preventing leakage of oil from the axle-box, and to the formation of the axle and the box; and it has for its objects, first, to dispense with the usual waste in the oil-well of the axle-box and substitute therefor a force 40 or paddle wheel mechanism and appropriate oil conductors or conveyers, whereby the oil is mechanically raised from the box oil-well to the top of the journal brass or bearing, and through which said oil finds its way to the axle- 45 journal; second, to provide an axle having a reduced portion or diameter in rear of the journal, and separated from the latter by a collar, said reduced portion having its location in the rear wall of the box, and serving to prevent 50 leakage from the box of any surplus oil supplied to the axle-bearing; third, to provide

an axle-box with an open top and a double chambered or recessed rear wall, each of which has a dust-excluder packing; and, finally, to provide a dust-shield so constructed that it automatically takes up its wear. Our invention accordingly consists of the combination, construction, and arrangement of parts, as hereinafter described and claimed. 55

In the drawings, A represents an axle-box, 60 which may be of any suitable construction and design and be provided with any desired form of lid and usual appurtenances; but we prefer to make it with an open top, a, which is closed by a cap or cover, B, extending the 65 length and width of the box, as shown, or otherwise, as desired. Both the cap B and box A are formed with aligning vertical openings c, through which pass bolts C, as more plainly shown in Fig. 9, for securing said parts, or 70 firmly bolting them together to form a tight joint between them, their meeting surfaces or edges being finished, if desired, or provided with a gasket or other packing. On the bottom and sides of box A, or otherwise located, 75 are guides or slotted brackets d, which receive sliding or vertically-moving bearing-blocks d', resting upon springs or other elastic supports, d'', the tendency of which is to move the blocks d' upwardly, or away from the floor or 80 bottom of box A.

In blocks d' is journaled a shaft, d'', on which is mounted a winged or paddle wheel, D, having end disks or collars, D' D', the periphery of which extends beyond the outer edges, f, 85 of the paddles, wings, or blades F. The shaft d'' and paddle-wheel D may be separately made, as shown, and are suitably connected; or they and the blades F may all be formed integral. Each of the blades F may be in one 90 piece of metal or other material, as indicated in Fig. 2, or be composed of sections f' and f'', the latter being radially adjustable upon the former, as represented in Fig. 7, and are made of leather, rubber, or other flexible material. 95

Upon the inner walls of the sides of box A, and at its forward end, are brackets g, having upper open end slots, g', into which passes a transverse check or guard bar, G, for preventing undue end movement of axle H. 100

On the inner wall of one of the sides of box

A are dovetail or other grooved tenons or guide-bars, *i*, which receive and firmly support a removable conduit or pipe, I, which extends upwardly along one side of the axle and is bifurcated at or near its upper end to provide two outlets, *i' i'*, bent at *i' i'* and projecting into chambers or recesses *k* of brass or bearing K. The mouth or inlet *i' i'* of conduit I is located opposite to and below the lower half of the paddle-wheel D, as shown more plainly in Fig. 2. The brass K has a central segmental or other configured transverse slot, *k'*, into which enters a correspondingly shaped and located rib, *b'*, on cap B, to form a key for holding the brass in position and for preventing longitudinal movement of same.

From the brass chambers or recesses *k* lead vertical or radial openings *k' 3*, for conducting the oil supplied to said chambers to the axle-journal. The operation of oiling the latter is as follows: The springs *d' 2* hold the disks *D' 1* of the paddle-wheel D in close contact with the journal *h*, so that as the latter revolves it communicates a rotary motion to the paddle-wheel D, whose blades sweep or force the oil in well *a' 1* into and up the conduit I, and thence into the brass-chambers *k*, from which it flows by way of openings *k' 3* to journal *h*. The wear of the disks *D' 1* is automatically taken up by the springs *d' 2*. The axle-box A has a triple rear wall, *A' A² A³*, inclosing vertical chambers *A⁴* and *A⁵*, of which the former has an open bottom, *a⁴*, and the latter an open top, *a⁵*. These walls are provided with the usual oval openings for the passage of the axle H, which has that portion of its length which is located in chamber *A⁴* reduced in diameter, as shown at *h²*, so as to provide a collar, *h³*, between the journal *h* and the reduced portion *h²*, for preventing surplus oil on the bearing or journal traveling back of the latter and leaking from the axle-box. To further avoid the last-named result, or to provide additional means for preventing oil-leakage from the box, and also to exclude dust therefrom, we place a guard or shield, L, in chamber *A⁴*. This guard is composed of two oppositely-arranged tapering or wedge-shaped followers, M M, having central openings or slots, *m*, for the passage of axle H, and flanges *m'*, with ribs or tenons *m²* at one of their edges or ends, as more plainly shown in Fig. 3.

Upon or attached to each follower is a wood or other suitable plate or packing, N, having central axle-openings, *n*, as illustrated. The outside surfaces, *n'*, of these plates are provided with grooves *n²*, into which are fitted gum or other gaskets, *n³*, which impinge against the opposite or adjacent transverse walls of chamber *A⁴*, as indicated in Fig. 1, and form a tight joint therewith. The followers M are so arranged that they contact or impinge upon one another between the wooden plates N to form a double wedge, (see Figs. 1 and 3,) the ribs *m²* of the followers entering plows or recesses *n⁴* in the plates N. Said followers are loosely secured together by

bolts *o*, which pass through elongated openings *o'* in their flanges *m'*. (See Figs. 4 and 9.) These bolts *o* project below the flange *m* of the lower follower, M, and are provided with expanding spiral or other springs, *o²*, a connecting spring seat or plate, *o³*, and fastening and adjusting nuts *o⁴*. Each plate N is kept in position upon its respective follower, 75 so as to move therewith, by the rib *m²* of the follower entering the plow or recess *n⁴* of the plate. The expansive action of the springs *o²* against the flange *m'* of the lower follower and the spring-plate *o³* tends to exert a downward 80 pressure upon the upper follower and its plate N, and upward pressure upon the lower follower and its attached plate, or tends to move or slide the followers upon one another, and, as they are tapering or wedge shape, any vertical movement of the followers moves the plates N laterally farther apart from one another, or increases the thickness of the guard or shield L in the direction of the axis of the axle to always automatically keep the gaskets 90 *n³* of plates N in close contact with the contiguous walls of chamber *A⁴* and edges *n⁵ n⁶* of the central openings of said plates in impingement with axle H, or its reduced portion *h²*, as shown, and thereby form a dust-tight joint 95 between said parts, the wear of which is always automatically taken up by the expansive force of the springs *o²*. The shield L not only provides a dust-excluder, but it also prevents leakage from box A of any oil that may escape from the oil-well *a' 1* or the journal bearing to the reduced portion of the latter. 100

In chamber *A⁵* is placed a secondary dust-excluding plate or shield, P, composed of a single piece of vulcanite, or of the usual material now employed for dust-shields for car-axle boxes. If desired, however, said shield P and its chamber *A⁵* may be dispensed with. The cap B is provided with an extension, B', for covering the top of chamber *A⁴*; but whenever deemed necessary such extension need not be used, in which case the chamber *A⁴* will then be open at both its top and bottom. 110

The box A is shown provided with side supports, Q, for the usual or other bearing-springs, and has openings *q* for the passage of the bolts which hold the bearing-springs and secure the axle-box to the car in the usual or well-known manner; but it is obvious that these spring-seats Q are dispensed with when 120 box A is placed in and has a vertical movement in the usual or other forms of pedestals.

If desired, oil-conduits I may be used on both sides of the axle-box, so that oil will always be supplied to the brass K, in whatever direction the axle may be rotated, or to provide for the lubrication of the axle-journal during a backward movement of a train or car. 125

If desired, the paddles of wheel D may be perforated to prevent undue resistance being offered to their passage or rotation through the oil in well or box A, and these perforations are plainly shown in Fig. 1.

It will be noted from the foregoing that the

- axle-journal is mechanically lubricated by the forcing of oil to its bearing, such forcing being effected by means of a paddle-wheel rotated by the axle; that a sectional follower dust-shield having automatically-acting mechanism for taking up the wear of its axle contact-surfaces is provided for excluding dust and preventing leakage of oil from the axle-box, and that the latter has an open top extending from end to end, whereby all the fixtures for the interior of the box may be easily placed therein and removed therefrom for repairs, renewal, or otherwise.
- What we claim is—
15. 1. The axle-box A, having chambers A⁴ and A⁵, dust shields or guards located in said chambers, and a removable top lid, B, with extension B', substantially as shown and described.
  20. 2. An axle-box having a rotating paddle-wheel located below the axle-journal and a vertical conduit leading from said wheel to the journal-brass, substantially as shown and described.
  25. 3. An axle-box having a rotating paddle or force wheel, spring-supports therefor, and a conduit having bifurcated or branched outlets leading into the axle brass or journal, substantially as shown and described.
  30. 4. In an axle-box, the combination of axle H, paddle-wheel D, conduit I, and bearing K, substantially as shown and described.
  35. 5. An axle-box having lugs i supporting removable conduit I, a paddle-wheel, D, brass K, and top lid, B, substantially as shown and described.
  40. 6. In an axle-box, the wheel D, having disks D', and blades f', provided with adjustable sections f'', substantially as and for the purpose set forth.
  45. 7. In an axle-box, the wheel D, having disks D', and perforated blades or paddles and spring-supported bearings, substantially as shown and described.
  50. 8. The axle-box A, having top lid, B, aligning-openings e' in said box and lid, fastening-bolts C, and side brackets, Q, having openings g, substantially as shown and described.
  9. A car-axle box having chamber A⁴, in combination with a dust guard or shield composed of wedge-shaped followers and packing-plates connected by spring-acting bolts, substantially as shown and described.
  10. A car-axle-box dust-shield composed of sliding wedge-shaped followers M M, packing-plates N N, and bolts or rods o, having springs o², and spring seat or bar o³, substantially as shown and described.
  11. A car-axle-box dust-shield composed of wedge-shaped followers M M, plates N N, gasket-rings n³ n³, and bolts o o, having springs o² o² and bar o³, substantially as shown and described.
  12. A car-axle having journal h, collar h³, and reduced portion h², as and for the purpose set forth.
  13. A car-axle box having two fixed chambers in its rear wall, one of which has an automatically-adjustable dust-shield and the other a single-plate shield, substantially as shown and described.
  14. A car-axle box having chambers A⁴ A⁵ and dust-shields L and P, the former composed of longitudinally-moving sections, substantially as shown and described.
  15. The box A, having removable oil-conduit I, paddle-wheel D, axle H, with reduced portion h², and collar h³, brass K, and dust-shield L, substantially as shown and described.
  16. In an axle-box, the brass K, having chambers k and ducts or outlets k³, in combination with conduit I and spring-supported paddle-wheel D, substantially as shown and described.
  17. The followers M M, having elongated openings o', bolts o, springs o², plate o³, and adjusting-nuts o⁴, substantially as and for the purpose set forth.
  18. The box A, having chamber A⁴, open at its bottom a⁴, in combination with a dust-shield, L, having sliding followers M M, bolts o, springs o², and plates o³, substantially as shown and described.
- In testimony whereof we affix our signatures in presence of two witnesses.
